FIG. 1.

FIG. 2.

Inventor,
Daniel L. Chandler,
By his attorney,
Charles S. Gooding.

UNITED STATES PATENT OFFICE.

DANIEL L. CHANDLER, OF FITCHBURG, MASSACHUSETTS, ASSIGNOR TO VEND-ADS CO. INC., OF WORCESTER, MASSACHUSETTS, A CORPORATION OF MASSACHUSETTS.

SOAP TABLET.

1,386,767.

Specification of Letters Patent. Patented Aug. 9, 1921.

Application filed May 31, 1919. Serial No. 300,906.

To all whom it may concern:

Be it known that I, DANIEL L. CHANDLER, a citizen of the United States, residing at Fitchburg, in the county of Worcester and 5 State of Massachusetts, have invented new and useful Improvements in Soap Tablets, of which the following is a specification.

This invention relates to an improved soap tablet and is particularly adapted to 10 be used by workmen, automobilists and others who are accustomed to use two kinds of soap in order to thoroughly cleanse their hands.

The object of the invention is to provide 15 a small, neat tablet of two kinds of soap, one kind of soap being known as a paste soap which is partially inclosed within a covering open at its opposite ends and comprising a different kind of soap, namely, an 20 ordinary toilet soap.

Another object of this invention is to provide a soap tablet which can be made by machinery and fed easily and practically in a coin-slot machine.

25 The paste soap is comparatively strong and is also soft and plastic as compared with the toilet soap.

Preferably, although not necessarily, the soap is inclosed in a covering of some water- 30 proof material, such as paraffin.

The invention consists in a soap tablet made of two different kinds of soap, the inner soap being a soft paste, the outer soap being comparatively hard and open at its 35 opposite ends, the whole preferably inclosed in a water-proof covering. The invention further consists in a soap tablet as herein-after set forth in the specification and particularly pointed out in the claims.

40 Referring to the drawings:

Figure 1 is a perspective view of my improved soap tablet.

Fig. 2 is a section taken on line 2—2, Fig. 1.

45 Like numerals refer to like parts in the two views of the drawings.

In the drawings, 5 is a core of soft or paste soap. 6 is a layer of comparatively hard toilet soap, and 7 is a water-proof 50 covering for both kinds of soap. This covering consists preferably of paraffin. The covering 7 is slotted at 8 for a portion of its length, so that it may be easily removed when it is desired to get at the soap inclosed 55 therein.

In order that the soap tablet may be easily and practically manufactured by machinery, the toilet soap 6 incloses the paste soap 5 in the form of an endless band open at its opposite ends, and this practical construction 60 also makes the soap tablet easy to separate into its different parts so that the user can readily obtain access to the paste soap and can easily separate it from its covering of 65 toilet soap.

The manner in which the article is used is as follows:

The user first removes the paraffin water- 70 proof covering 7 by lifting the same adjacent to the split portion 8 and then peeling the cover off of the soap. He then breaks the hard soap 6 apart and removes the paste soap 5 from the interior thereof. He then gives his hands a first washing with the paste soap, and after thoroughly wash- 75 ing them with the paste soap he washes them again with the toilet soap, and finally rinses them.

I claim:

1. A cleansing tablet comprising a core 80 of paste soap and a relatively thin frangible layer of comparatively hard soap consisting of an endless imperforate band entirely surrounding said core except at the opposite ends thereof.

2. A cleansing tablet comprising a core of paste soap and a relatively thin frangible layer of comparatively hard soap consisting of an endless imperforate band entirely 90 surrounding said core except at the opposite ends thereof, and a waterproof covering surrounding said tablet except at the opposite site ends thereof.

3. A cleansing tablet comprising a core of paste soap and a layer of comparatively 95 hard soap consisting of an endless imperforate band entirely surrounding said core except at the opposite ends thereof, and a waterproof covering surrounding said tablet except at the opposite ends thereof, said 100 covering being slotted for a portion of its length from one end of said tablet.

In testimony whereof I have hereunto set my hand in presence of two subscribing witnesses.

DANIEL L. CHANDLER.

Witnesses:

CHARLES T. FLYNN,
